HYMAN MAIMIN, OF NEW YORK, N. Y.

BELT-DRIVE FOR SEWING-MACHINE MOTORS.

1,377,019.

Specification of Letters Patent.

Patented May 3, 1921.

Application filed December 22, 1919. Serial No. 346,704.

To all whom it may concern:

Be it known that I, HYMAN MAIMIN, a citizen of the United States, residing at New York city, in the county of New York, State 5 of New York, have invented certain new and useful Improvements in Belt-Drives for Sewing-Machine Motors; and I do hereby declare the following to be a full, clear, and exact description of the invention, such as 10 will enable others skilled in the art to which it appertains to make and use the same.

This invention relates to belt drives for sewing machine motors.

Small electric motors are now generally 15 used for driving sewing machines, especially in the case of machines that are to be used continuously, as in the garment industry. It is customary to provide the motors with rheostats to prevent a sudden rush of current 20 when the motors are started under load and also to permit the speed of the machines to be controlled while they are in operation. The disadvantages of rheostats, particularly their cost and liability to get out 25 of order, have led to the production of many arrangements for avoiding their use by running the motors continuously and bringing them into operative relation to the machines whenever it is desired that the latter 30 be driven. In some of these prior arrangements the motors are fixed upon the tables of the sewing machines and connected to frictional wheels which are adapted to be swung into engagement with the hand 35 wheels of the machines whenever it is desired to operate the latter. These arrangements, however, require the use of extra members and in some cases, owing to the movement of the swinging members upon 40 which the friction wheels are carried, there is a change in the tension of the driving belt.

In power drives for sewing machines, particularly in the garment industry, the mechanism should be arranged so that the machines may be normally operated at a pre-determined speed to which the operator is required to conform in the performance of his part of the work. In many of the prior 45 arrangements which have been proposed for eliminating the use of rheostats, the speed of the machines is directly under the control of the operators and depends upon the effort expended by them in holding the motors in 50 operative relation to the machines. In the case of a slow operator it will be compara- 55

atively easy for him to prevent his machine from being driven at the required speed, with the result that his production will be cut down, and the motor will not be operated at its full load.

It has been proposed to overcome the disadvantages mentioned above by pivoting the motor adjacent the hand wheel or driving pulley of a sewing machine in such a manner that it may be thrown into or withdrawn from operative relation to the machine by tilting the motor about its pivot. This arrangement further provides that the speed at which the machine is driven by the motor 70 will under normal conditions be of a predetermined amount and will not be as subject to variations in the effort expended by the operator as are prior arrangements of this general character. The arrangement does, 75 however, permit the operator to change the speed of the machine from time to time as may be required, but this alteration necessitates a special act on his part which will not naturally be performed under normal 80 conditions of operation. In one embodiment of the invention described above, power may be transmitted from the motor to the machine by a pulley on the shaft of the motor which is connected by a belt to a driving 85 pulley on the shaft of the machine, the motor being arranged to fall away from the machine to apply tension to the driving belt. The position of the motor is controlled by a treadle in order that the hands of the 90 operator may be free for manipulating his work. The treadle which is normally actuated by a spring to swing the motor in such a manner as to slacken the driving belt has a flexible or lost motion connection to 95 the motor so that when the effect of the spring is overcome by pressure upon the treadle, the flexible connection will become slack to permit the motor to fall away from the machine and hold the driving belt under 100 tension by the weight of the motor independently of the effect of the actuating spring. The arrangement does, however, permit the speed of the machine to be controlled, for, if the treadle is not pressed 105 downwardly to its full extent, the flexible connection will remain taut and balance the motor so that the effect of its weight in producing belt tension will be partly overcome, and due to the slip between the belt 110 and the pulleys there will be a resulting decrease in the speed of the machine.

With the arrangement discussed above when it is desired to stop the machine it is necessary to swing the motor toward the machine to slacken the belt sufficiently to prevent it from transmitting any power.

It is an object of the invention of this application to provide an arrangement whereby the belt may be maintained under substantially constant tension, due to the weight 10 of the motor and may be shifted from a loose to a fast pulley on the motor shaft to start the machine, or in a reverse direction to stop the machine. The shifting mechanism is preferably under the control of a 15 foot of the operator so that both hands are free for manipulation of his work. The normal condition of the apparatus is such that the belt is held upon the loose pulley by the force of the spring acting upon a treadle, 20 but when the spring is overcome by pressure upon the treadle, the device operates to shift the belt to the fast pulley with which it is held in contact under conditions of substantially constant tension.

25 The invention thus provides an arrangement in which the motor may be driven continuously and conveniently and quickly brought into operative relation to the machine or removed therefrom as may be desired. When in operative relation the motor 30 will drive the machine at the predetermined speed required for most efficient operation, and this speed cannot readily be altered by the operator.

35 In some cases, however, it may be necessary to permit the operator to exercise a control over the speed of the machine, and for this purpose the motor may be mounted so that it may be tilted about its pivot point 40 after the belt has been shifted to permit the speed of the machine to be varied in the same manner that it is controlled in the arrangement of my copending application mentioned above. For the sake of simplicity 45 the apparatus is so constructed that there is a single operating connection between the treadle and the motor, and the belt shifting mechanism is controlled by the initial movement of the motor as it falls away from the 50 machine to cause the belt to be shifted to the fast pulley. After the belt has been shifted the motor may swing through a further arc to tighten the belt. The treadle is actuated by a spring to restore the parts to their normal condition, and as in the case of the arrangement of my copending application mentioned above, there may be a flexible or 55 lost motion connection between the treadle and the motor so that the normal movement 60 imparted to the treadle will be sufficient to slacken the flexible connection so that the motor will produce tension in the driving belt independently of the effect of the treadle spring after the belt has been shifted. The 65 natural condition of operation will be such

that the operator will find it most convenient to hold the treadle completely depressed so as to release the flexible connection sufficiently to permit the motor to be held in operative relation to the belt by its own weight after the belt has been shifted, and it will be somewhat more tedious for the operator to hold the treadle in such a position that the flexible connection will remain taut and balance the weight of the motor so as to partially overcome the effect of the weight of the motor in producing belt tension.

70 The particular nature of the invention, as well as other objects and advantages thereof, 80 will appear more clearly from a description of certain preferred embodiments as illustrated in the accompanying drawings, in which—

85 Figure 1 is an end elevation of a sewing machine having the belt shifter applied to the motor;

90 Fig. 2 is a rear elevation of the frame of the machine with the apparatus in place thereon;

95 Fig. 3 is an enlarged detailed view of a belt shifter;

Fig. 4 is an end elevation of a sewing machine in which the movement of the motor shifts the driving belt and controls the tension of the same;

100 Fig. 5 is a rear elevation of the apparatus of Fig. 4; and

Fig. 6 is an enlarged detail view showing the belt shifter of Figs. 4 and 5.

105 The sewing machine illustrated somewhat diagrammatically in the drawings comprises a table 10 carried upon standards 11 and serving as a support for the frame 12 which comprises a vertical portion and a horizontal portion carrying at its outer end the usual member within which the mechanism for reciprocating the needle is mounted, this mechanism being driven by a shaft carrying a belt pulley 13, and hand wheel 14. Mounted adjacent the hand wheel is an electric motor 15 which as shown herein is carried upon a bracket like that disclosed in my copending application, Serial No. 343,215, filed December 8, 1919, but it will be understood that the motor may be supported adjacent the machine wheel in any other suitable manner, as for instance, by being mounted directly upon the table of the machine, particularly in case the arm of the machine carries mechanism which might interfere with the application of a bracket.

110 The supporting bracket shown herein comprises a member 16, having at its inner end upper and lower extensions 17 and 18, respectively, adapted to fit over the top and bottom of the horizontal arm of the frame 12. The supporting member is bent outwardly as indicated in Fig. 1 to clear the machine wheel and bring the motor in 115 120 125 130

proper relation to this wheel. In the supporting member constructed as above described, the weight of the motor upon the end of the member will produce a turning 5 moment which will be opposed by the engagement of the upper and lower extensions with the frame so that the member may be held in place upon the frame without any other means. In practice, however, it is 10 preferable to provide an auxiliary supporting member 19 to coöperate with the main supporting member and hold it more securely upon the machine frame to prevent displacement or dislodgement due to the 15 vibration of the motor, or from any other cause. This auxiliary supporting member consists of a strip of metal or other suitable material having a flat upper portion adapted to be seated upon the top of the machine 20 frame and provided with apertures through any one of which the usual spool spindle 20 may be passed to hold the supporting member more securely in place upon the frame. The depending portion of the strip is turned 25 upwardly to form a hook within which the main supporting member is seated as shown most clearly in Fig. 2. The outer end of the supporting member 16 is bent at right angles to form an ear 21. Another ear may 30 be formed by cutting a portion of the supporting member 16 and bending it at right angles. The ears carry a pin 22 which passes through lugs 23 associated with the motor casing. Placed upon the pin 22 between the motor lugs is a split clamp 24 of 35 any suitable construction which serves to hold the motor in proper position longitudinally of the bracket.

The supporting bracket 16 is so constructed as to bring the pivot pin 22 in 40 proper relation to the driving pulley of the machine to permit the motor to fall away from the machine to maintain tension in the driving belt 25 which passes over the 45 machine pulley 14 and over one or the other of a pair of adjacent loose and fast pulleys 26 and 27, respectively, mounted on the shaft of the motor.

For the purpose of throwing the belt 25 50 from one pulley to the other, there is provided a lever 28 pivotally mounted upon a bracket 29 attached to the casing of the motor. The lever is provided with an extension 30 having a forked outer end 31 55 adapted to engage the belt to shift the latter from one pulley to the other when the lever is rocked. The bracket 29 may be provided with stops 32 and 33 to limit the movement of the belt shifter to prevent it from throwing 60 the belt off of either of the pulleys. One end of the lever 28 is weighted as at 34, and to the other end of the lever is connected a link 35 which is adjustably connected, as by means of a clamp 36 to a flexible connection 65 37 which is attached at its other end to a

treadle 38 mounted upon a base 39 which may be placed in convenient position to be reached by the operator's foot. Beneath the treadle is a spring 40 which normally raises the treadle into the position shown in 70 Fig. 1.

In the operation of the mechanism described above, the spring 40 normally holds the treadle 38 in elevated position, and by means of the flexible connection 37 and link 75 35 the lever 28 of the belt shifter is held in position to keep the belt upon the loose pulley, so that although the motor be running, no power will be transmitted from it to the machine. When it is desired to drive 80 the machine, the treadle 38 will be depressed against the effect of spring 40 to permit the lever 28 to turn under the influence of its weight 34 and shift the belt from the loose pulley 26 to the fast pulley 27, the extension 85 30 engaging the stop 33 to limit the movement of the shifter and prevent it from throwing the belt off of the pulley. Power will immediately be transmitted to the machine which will continue in operation until 90 the belt is thrown to the loose pulley by removing the foot from the treadle so that the spring 40 will be free to exert its force in tilting the lever 28 into position to shift the belt onto the loose pulley 26, the extension 95 30 at this time engaging the stop 32 to limit its movement. By virtue of the arrangement by which the motor is supported so that its weight produces tension in the driving belt, the motor may swing slightly about 100 the pivot pin 22 as the belt is shifted from one pulley to the other, but it will not be possible for the operator to alter the normal position of the motor, at least by manipulation of the treadle, so that he will be unable 105 to decrease the speed of his machine unless he should attempt to do it by tilting the motor with one of his hands, but he could not well perform such an act without interfering with his work and rendering it subject to detection.

For certain classes of work it may be necessary to provide an arrangement whereby the operator may alter the speed of his machine from time to time, and in Figs. 115 4, 5 and 6 of the drawings there is shown such a modification of the apparatus. In these figures the motor 15 is mounted upon a bracket 16 in the same manner as in the embodiment of the invention shown in the 120 preceding figures, but the cord 37 instead of being connected to a belt shifter is attached to a lug 41 on the side of the motor lying toward the machine so that the normal action of the spring 40 is to draw the 125 motor toward the machine to slacken the belt and prevent it from transmitting motion to the wheel of the machine. In order to prevent the motor from being thrown over its pivot, in which case it would fall 130

toward the machine, there is a stop 42 consisting of a pin inserted in the ear 21 of the bracket and adapted to be engaged by one of the lugs on the motor, in order to 5 limit the movement of the latter.

The motor shaft is provided with a loose pulley 43 and a fast pulley 44, both of these pulleys being provided at their outer ends with relatively high flanges 45 to prevent 10 any danger of the driving belt 25 being thrown off of the pulleys while it is being shifted, or while it is slack.

The mechanism for effecting the shifting of the belt comprises a lever 46 pivotally 15 mounted upon the bracket 16 and provided with a forked extension 47 to engage the belt. The other end of the lever is provided with a weight 48, and between the weight and the pivot of the lever is a slot 49 which 20 receives a pin 50 on the end of a bracket 51 attached to the motor. A stop pin 52 projecting from bracket 16 limits the downward movement of the lever.

The elements of the mechanism are so constructed and related to each other that when 25 the treadle 38 occupies its normal position under the influence of spring 40, the connection 37 will draw the motor into a position such as shown in Fig. 4 in which the shaft 30 of the motor lies on a line A passing through the pivot pin of the motor. When the motor occupies this position the bracket 51 will through its pin and slot connection with lever 46 elevate the latter into the position shown in Fig. 5 and hold the driving belt 25 upon the loose pulley 43 so that no power will be transmitted to the machine, and since the motor is drawn toward the machine the belt will be relatively slack.

40 When it is desired to drive the machine the operator depresses the treadle 38 to overcome the effect of the spring 40 and release the connection 37 to permit the motor to fall away from the machine. This 45 movement of the motor will be accompanied by a corresponding movement of the bracket 51 which will release the lever 46 so that under the influence of the weight 48 the lever will fall upon the stop 52 and shift 50 the belt 25 from the loose pulley 43 to the fast pulley 44. It is intended that the shifting of the belt shall occur during the initial movement of the motor away from the machine as the treadle is depressed, but 55 on account of the slot 49 the motor may continue its movement away from the machine after the belt has been shifted. Under normal conditions of operation the treadle 38 will be depressed until its outer end rests 60 upon the base 39, in which case the motor will fall into a position in which its weight will produce such a tension in the belt as to drive the machine at the predetermined speed for most efficient operation. Preferably 65 the flexible connection 37 should be of

such a length that when the treadle 38 occupies its completely depressed position the connection will become slack so that the belt tension produced by the weight of the motor will not be lessened by the opposing 70 effect of the spring 40. The motor will thus be free to drive the machine at the predetermined speed regarded as suitable for most efficient operation.

In case it is desired to lessen the speed, 75 the treadle will be lifted sufficiently to take up the slack in the flexible connection and then pull the latter enough to partially overcome the effect of the weight of the motor upon the tension of the belt. There 80 will thus be produced between the belt and the pulleys to which it is connected at this time, a certain amount of slip which will result in a decreased speed of operation of the machine without changing the speed of 85 the motor by means of a rheostat or similar device. During such movements of the motor the pin 50 will move freely in the slot 49 of the lever 46 without lifting the lever, so that the belt will not be shifted from the 90 fast pulley. When it is desired to stop the machine the treadle will be released to permit the spring 40 to elevate it into its normal position and through the connection 37 swing the motor toward the machine. As 95 the motor swings the pin 50 will engage the upper end of the slot 49 and lift the lever 46 into the position shown in Fig. 5, at the same time shifting the belt to the loose pulley. By providing the flanges 45 upon the 100 pulleys there is no danger of the belt being thrown off of either of the pulleys, even if shifted quickly by a sudden actuation or release of the treadle, or if allowed to lay slack upon the fast pulley.

105 The invention thus provides a motor drive for a sewing machine which is of simple construction and eliminates the use of a delicate and expensive instrument such as a rheostat for controlling the speed of the 110 motor. Since the motor is continuously running at high speed the machine starts quickly whenever the belt is shifted onto the fast pulley and tightened. The arrangements of the invention insure that under normal conditions of operation the sewing machine shall be driven at maximum speed so that the efficiency of the operator is not lessened. To meet the cases in which it is desired that the operator may exercise 115 some control over the speed of the machine the invention provides an arrangement in conjunction with the belt shifter for producing changes in the speed of the machine by changes in the position of the motor, and 120 preferably the arrangement is such that these changes require that the operator hold the treadle in an intermediate position which is not only less comfortable, but renders it more difficult to maintain a constant 125 130

speed of the machine than when the treadle is in fully depressed position, which is in the nature of a stop position and may be maintained by the operator with comparatively little effort. In both of the embodiments of the invention illustrated herein the usual condition of the machine will be either one in which the motor is entirely out of operative relation to the machine, due to the 10 driving belt being held upon the loose pulley by the effect of the spring acting upon the treadle, or one in which the motor is in operative relation to the machine on account of the belt being shifted to the fast 15 pulley, in which case the tension of the belt is maintained by the weight of the motor independently of the spring. However, it is possible by employing the arrangement shown in Figs. 4, 5 and 6 to produce a third 20 condition in which the motor is held in operative relation to the machine under the balanced effect of its weight and the force exerted by the spring so that changes in speed of the machine may be obtained. 25 While certain preferred embodiments of the invention have been shown and described, it will be understood that various changes in the details of construction may be made without departing from the principle of the invention as defined in the appended claims.

Cross reference is hereby made under the provisions of Rule 43, to copending application, Serial No. 343,216, filed December 35 8, 1919.

I claim:

1. In a sewing machine provided with a driving wheel, the combination of a pivotally mounted motor provided with fast and 40 loose pulleys, a belt associated with the pulleys and the driving wheel of the machine and adapted to be held under tension by the weight of the motor, and means mounted on the motor for shifting the belt 45 from one pulley to the other.

2. In a sewing machine provided with a driving wheel, the combination of a pivotally mounted motor provided with fast and loose pulleys, a belt associated with the 50 pulleys and the driving wheel of the machine and adapted to be held under tension by the weight of the motor, a lever mounted upon the motor and provided with a belt engaging member, means for actuating the 55 lever to shift the belt from one pulley to the other and adapted to be overcome by the operator to release the lever to permit it to shift the belt in the opposite direction.

3. In a sewing machine provided with a 60 driving wheel, the combination of a pivotally mounted motor provided with fast and loose pulleys, a belt associated with the pulleys and the driving wheel of the machine and adapted to be held under tension 65 by the weight of the motor, a weighted

lever mounted upon the motor and provided with a belt engaging member, a spring for swinging the lever against the effect of the weight to shift the belt from one pulley to the other, and adapted to be overcome by 70 the operator to permit the lever to be swung by its weight to shift the belt in the opposite direction.

4. In a sewing machine provided with a driving wheel, the combination of a pivotally mounted motor provided with fast and loose pulleys, a belt associated with the pulleys and the driving wheel of the machine and adapted to be held under tension 75 by the weight of the motor, a lever mounted adjacent to the motor and provided with a belt engaging member, means for actuating the lever to shift the belt from the fast pulley to the loose pulley and adapted to be overcome by the operator to release the lever 80 to permit it to shift the belt from the loose pulley to the fast pulley.

5. In a sewing machine provided with a driving wheel, the combination of a pivotally mounted motor provided with fast and 90 loose pulleys, a belt associated with the pulleys and the driving wheel of the machine and adapted to be held under tension by the weight of the motor, a lever mounted adjacent the motor provided at one end with 95 a weight and having a belt engaging member, means connected to the other end of the lever for swinging the lever to shift the belt from one pulley to the other, and adapted to be overcome by the operator to permit the 100 weight to swing the lever to shift the belt in the opposite direction.

6. In a sewing machine provided with a driving wheel, the combination of a pivotally mounted motor provided with fast and 105 loose pulleys, a belt associated with the pulleys and the driving wheel of the machine, and means mounted on the motor for shifting the belt from one pulley to the other.

7. In a sewing machine provided with a 110 driving wheel, the combination of a motor provided with fast and loose pulleys, a belt associated with the pulleys and the driving wheel of the machine, a lever mounted adjacent the motor and provided at one end 115 with a weight adapted to swing the lever in a direction to shift the belt from the loose pulley to the fast pulley and means attached to the other end of the lever for overcoming the effect of the weight to swing the lever 120 in a direction to shift the belt from the loose pulley to the fast pulley, said means being adapted to be overcome by an operator to permit the weight to function.

8. In a sewing machine provided with a 125 driving wheel, the combination of a motor provided with fast and loose pulleys, a belt associated with the pulleys and the driving wheel of the machine, a bracket attached to the motor and provided with a pair of stops, 130

- a lever pivotally attached to the bracket and provided with an extension lying between the stops and having a belt engaging fork at its outer end, a weight at one end of the 5 lever for rotating the same to shift the belt from the loose pulley to the fast pulley, a treadle, a connection between the treadle and the other end of the lever and a spring for 10 swinging the treadle to rotate the lever in a direction to lift the weight and shift the belt from the fast pulley to the loose pulley.
9. In a sewing machine provided with a driving wheel, the combination of a motor provided with fast and loose pulleys, a belt 15 associated with the pulleys and the driving wheel of the machine, a weighted lever mounted adjacent the motor and provided with a belt shifting member, a member connected at one end to the lever and a spring- 20 pressed treadle to which the other end of the member is connected and adapted when in one extreme position to hold the lever in position to hold the belt upon the loose pulley and when in another extreme position to release the member sufficiently to 25 permit the lever to swing under the influence of its weight to shift the belt onto the fast pulley to drive the machine.
10. In a sewing machine provided with a 30 driving wheel, the combination of a pivotally mounted motor provided with fast and loose pulleys, a belt associated with the pulleys and the driving wheel of the machine and adapted to be held under tension by the 35 weight of the motor, means for swinging the motor toward the machine to produce slack in the belt, and adapted to be overcome by the operator to permit the motor to swing away from the machine to tighten 40 the belt, and means actuated by the motor

as it swings away from the machine to shift the belt from the loose pulley to the fast pulley.

11. In a sewing machine provided with a driving wheel, the combination of a pivotally mounted motor provided with fast and loose pulleys, a belt associated with the pulleys and the driving wheel of the machine and adapted to be held under tension by the weight of the motor, a belt shifter, 50 means for swinging the motor toward the machine to produce slack in the belt and actuate the shifter to move the belt onto the loose pulley, said means being adapted to be overcome by the operator to permit the motor to swing away from the machine to tighten the belt and actuate the shifter to move the belt onto the fast pulley. 55

12. In a sewing machine provided with a driving wheel, the combination of a pivotally mounted motor provided with fast and loose pulleys, a driving belt associated with the pulleys and the driving wheel of the machine and adapted to be held under tension by the weight of the motor, a belt 60 shifter mounted adjacent the motor, means associated with the motor for controlling the movement of the belt shifter, means for swinging the motor toward the machine to produce slack in the belt and through said 65 controlling means actuate the shifter to move the belt onto the loose pulley, said swinging means being adapted to be overcome by the operator to permit the motor to swing away from the machine to release the 70 shifter to move the belt onto the fast pulley and tighten the belt so that the machine may be driven. 75

In testimony whereof I affix my signature.
HYMAN MAIMIN.
